METHOD OF ESTABLISHING BLEED LINES
ON PRINTING SURFACESOwen R. Huggins, South Norwalk, Conn., as-
signor to Linotone Corporation, a corporation
of New York

Application March 26, 1938, Serial No. 198,219

7 Claims. (Cl. 95—5.7)

This invention relates to the production of etched printing surfaces, and it is concerned, more particularly, with the production of etched printing surfaces by photo-mechanical methods, 5 for printing on textiles and the like.

Various photo-mechanical methods have already been proposed for producing such printing surfaces, but these methods have met with little or no success from a commercial standpoint, as 10 evidenced by the fact that, in general, such surfaces are still being produced by the old and well known pantograph method, which method is a long, tedious, and expensive operation, particularly when the design is made up of a mult- 15 ility of design elements.

The present invention aims to avoid these objectionable factors, and to so simplify the operation that printing surfaces may be produced speedily, accurately, and at little expense as compared with the more complicated procedures heretofore employed.

For a complete description as to how the improved process is carried out reference may be made to the accompanying drawing wherein the 25 design to be etched on the printing member is shown, by way of example, as being circular in form. It is to be understood, however, that the invention is not limited to the production of this particular design on a printing member, but is 30 applicable as well to the production of other designs of different forms.

Referring to the drawing:

Fig. 1 is a side elevational view of apparatus employed in practicing the present invention; 35 Fig. 2 is a front elevational view showing a positive of a design element mounted on a copy board positioned in front of a camera;

Fig. 3 is a diagrammatic view showing a marginally reduced reproduction of the design ele- 40 45 giment obtained when a light sensitive member in the camera is exposed and the copy board re- volved edgewise in a circular path, the light sen- sitive coating by means of a special developing process being removed from that portion of the member which was subjected to the action of light during exposure when the copy board was revolved;

Fig. 4 is a diagrammatic view showing the 50 55 marginal band obtained by subjecting the outer portion of the unaffected reproduction to the action of light when the copy board is revolved in a circular path having a greater radius;

Fig. 5 is a diagrammatic view showing a screen 55 positioned in front of the marginally reduced

reproduction preparatory to the third or last exposure; and,

Fig. 6 is a diagrammatic view showing the final negative obtained by means of the usual developing process when the coating on the member is 5 developed.

In practicing this invention, a positive 10 comprising a non-light reflecting reproduction 11 of a design element is created on a light reflecting surface 12 either by hand or by photography. 10 The positive 10 is mounted on a copy board 13 which, as shown in Fig. 1, is positioned before the lens of a camera 14 and light from any suitable source is directed against it. The copy board 13 is then moved edgewise in a circular path 12 on a given radius, as indicated in Fig. 2, and while the copy board 13 is in motion a light sensitive member, such as a film or plate, 15 positioned in the camera, is exposed to the positive 10 to create a light unaffected marginally reduced reproduction 16 of the design element. For details of the method of and means for so creating a marginally reduced reproduction of a design element, reference may be made to my co-pending application Serial No. 146,218 filed June 3, 1937. 25

The light sensitive member 15 is then removed from the camera and developed, and treated with a reversing solution, as for instance, in a weak solution of sulphuric acid and potassium bichromate, so as to remove the light sensitive emulsion from that portion of the member which was exposed to light and leave intact the unaffected marginally reduced reproduction 16 (see Fig. 3).

The light sensitive member 15 is now put back 35 into the camera 14 in its original position and the copy board 13 is adjusted so that the light unaffected marginally reduced reproduction 16 of the design element 11 is centered in exact register with the non-light reflecting reproduction 11 of the design element on the positive 10. 40

The copy board 13 is again moved edgewise or revolved in a circular path having a slightly greater radius; and as it revolves a second exposure is made so that a marginal band 17 of the 45 reproduction 16 of the design element is subjected to the action of light reflected back from the light reflecting surface 12 of the positive 10 (see Fig. 4).

After this exposure a plain light reflecting surface is positioned between the lens of the camera and the positive 10 and the light sensitive member 15 is exposed thereto through a screen 18 (see Fig. 5). The member 15 is then removed from the camera and developed in the usual way 55

to fix the areas exposed to the action of light. After such development the member 15 will comprise (as shown in Fig. 6) an opaque band 20 which defines the outline of the marginally reduced reproduction 16 and a plurality of transparent and opaque areas 21 and 22 respectively within the confines of the band 20. The developed member 15 may now be placed in intimate contact with a light sensitive coating on a printing member and subjected to the action of light, the coating on the member developed to fix the areas exposed to the action of light, washed and subjected to the action of acid to etch out on the printing member the areas shielded against the action of light by the opaque portions. Thus a marginally reduced reproduction of the design element may be created on the printing member comprising a color carrying groove which defines the outline of the design element and a plurality 20 of color carrying cells or pockets and unetched areas within the confines of this groove.

While in the above described arrangement, the screen is photographed onto the light sensitive member after the marginal band is created 25 equally favorable results may be obtained by photographing it onto the member before the marginal band is created.

Having thus described my invention, I claim:

1. In a process of producing printing surfaces, the steps which include creating a positive comprising a non-light reflecting reproduction of a design element on a light reflecting background, so exposing a light sensitive member to said positive that a marginally reduced reproduction of said design remains unaffected by light, treating said member to remove only that portion of the sensitized surface of the member affected by light during said exposure, exposing to the action of light a marginal band around the periphery of the reduced reproduction which remained unaffected during the first exposure of the member, and developing said member.

2. In the process of producing printing surfaces, the steps which include creating a positive comprising a non-light reflecting reproduction of a design element on a light reflecting background, so exposing a light sensitive surface to said positive that a marginally reduced reproduction of said element remains unaffected, removing from said member the light sensitive surface subjected to the action of light during the creation of said reduced reproduction, exposing a marginal band around the periphery of the reduced reproduction to the action of light, photographing a screen within the boundary of the marginally reduced reproduction, and developing the member.

3. In the process of producing printing surfaces, the steps which include creating a positive having a non-light reflecting reproduction of a design element, exposing a light sensitive member to said positive, creating movement between said positive and said member during said exposure to create a marginally reduced light unaffected reproduction of the element on the member, removing from said member the light sensitive surface subjected to the action of light during the creation of said reduced reproduction, exposing a marginal band around the periphery of the reduced reproduction to the action of light, and developing the member.

4. In the process of producing printing surfaces, the steps which include creating a positive having a non-light reflecting reproduction of a

design element, exposing a light sensitive member to said positive, revolving said positive in a circular path during said exposure to create a light unaffected marginally reduced reproduction of the element on the member, removing 5 from said member the light sensitive surface subjected to the action of light during the creation of said reduced reproduction, exposing a marginal band around the periphery of the reduced reproduction to the action of light, and developing 10 the member.

5. In the process of producing printing surfaces, the steps which include creating a positive having a non-light reflecting reproduction of a design element, exposing a light sensitive member to said positive, revolving said positive in a circular path during said exposure to create a light unaffected marginally reduced reproduction of said element on the member, removing from 15 said member the light sensitive surface subjected to the action of light during the creation of said reduced reproduction, again exposing the member to the positive, revolving the positive during said second exposure in a circular path having a radius greater than the radius of the 20 circular path through which it was revolved during the first mentioned exposure to expose a marginal band around the periphery of the reduced reproduction to the action of light, and developing the member.

6. In the process of producing printing surfaces, the steps which include creating a positive comprising a non-light reflecting reproduction of a design element on a light reflecting background, exposing a light sensitive member to said positive, revolving said positive in a circular path during said exposure to create a marginally reduced light unaffected reproduction of the element on the member, removing from said member the light sensitive surface subjected to the 35 action of light during the creation of said reduced reproduction, again revolving said positive during said second exposure in a circular path having a radius greater than the radius of the 40 circular path through which it was revolved during the first mentioned exposure to expose a marginal band around the periphery of the reduced reproduction to the action of light, photographing a screen onto the reduced reproduction, and developing the member.

7. In the process of producing printing surfaces, the steps which include creating a positive comprising a non-light reflecting reproduction of a design element on a light reflecting background, exposing a light sensitive member 55 to said positive, revolving said positive in a circular path during said exposure to create a marginally reduced light unaffected reproduction of the element on the member, subjecting the member to the action of a reversing solution to remove from said member the light sensitive surface subjected to the action of light during the creation of said reduced reproduction, again revolving the member during said second exposure in a circular path having a radius greater than 60 the radius of the circular path through which it was revolved during the first mentioned exposure to expose a marginal band around the periphery of the reduced reproduction to the action of light, photographing a screen onto the 65 reduced reproduction, and developing the member.

OWEN R. HUGGINS.
